SCREENED CLOSURE CONSTRUCTION

Samuel B. Zimmer, Los Angeles, Calif., assignor
to H. W. Ritz, Los Angeles, Calif.

Application March 26, 1931, Serial No. 525,534

15 Claims. (Cl. 189—69)

This invention relates to closure constructions, and has for an object the provision of a closure construction which represents an improvement over that disclosed in my allowed application 5 Serial No. 314,706, filed October 24, 1928, issued April 7, 1931 as Patent 1,799,719.

The closure construction of my aforesaid application comprises a hinged closure, such as a sash, and a hinged screen so disposed with relation to a window or other opening that the screen is toward the inside with respect to the closure, permitting the closure to open outwards from its casement without having to leave the screen also in open position.

15 The present invention contemplates the adaptation of substantially the same principle to metal sash and casement constructions, it being understood that the device of the allowed application has been applied specifically to other constructions.

20 A more detailed object is to provide a closure construction in the form of a casement having a closure, such as a conventional steel frame sash hinged thereupon upon adjustable hinges, permitting the insertion of a screen frame or an auxiliary sash frame between the casement and the first mentioned sash frame, both frames being mounted for pivotal movement about a common axis in being swung to and from closed position.

25 Another object is to provide an auxiliary frame as described, which is receivable between the main sash frame and the casement, and which is adapted to maintain a plurality of lines of engagement of the closure with the casement, these lines substantially encircling the opening of the casement so as to provide a multiple seal when the closure is in closed position.

30 A further object is to provide a novel hinge construction, whereby the adjustment of the main closure necessary for the insertion of the auxiliary frame, is made possible.

35 A still further object is to provide novel means for mounting the screen or auxiliary frame upon the same hinges as those upon which the main closure frame is mounted, this mounting means permitting facile removal and replacement of the screen or auxiliary frame whenever desired, thus facilitating the operation of washing the pane or panes of glass in the closure frame.

40 The invention possesses other objects and advantageous features, some of which, with those enumerated, will be set forth in the following description of the invention's particular embodiments which are illustrated in the drawings ac-

companying and forming a part of the specification.

Referring to the drawings:

Fig. 1 is a horizontal sectional view taken through a double window casement, and showing the manner of mounting closure frames and screen frames thereupon in accordance with the principles of the present invention.

Fig. 2 is an enlarged horizontal sectional view similar to Fig. 1, but showing only one side of the double window casement. A portion of the figure is broken away to reduce its size.

Fig. 3 is a view in elevation, showing one of the hinges whereby the closure and screen frames are hung upon the casement. The direction of view 70 is indicated by the arrow 3 of Fig. 2 and a portion of the figure is broken away to reveal the interior construction.

Fig. 4 is a detail vertical sectional view of the pintle portion of the hinge of Fig. 3. The plane of 75 section is indicated by the lines 4—4 of Figs. 2 and 3, and the direction of view by the arrows.

Fig. 5 is a plan view of the bushing which forms a portion of the hinge of Figs. 2, 3 and 4.

Fig. 6 is a side elevation of the pintle portion 80 of a slightly modified form of hinge construction.

Fig. 7 is a top plan view, the direction of view being indicated by the arrow 7 of Fig. 6.

Fig. 8 is a vertical sectional view taken upon the line 8—8 of Fig. 7, with the direction of view as 85 indicated.

Fig. 9 is an enlarged view similar to Fig. 8 but showing the hinge leaf associated with the sash frame in its alternative position.

Fig. 10 is a perspective view of the hinge and 90 portions of the sash and screen frames of Figs. 1, 2, and 3.

The conventional construction of steel window casements and sash frames is such that a double weather seal encircling the opening of the casement is established when the sash frame is moved to closed position, inasmuch as the sash frame makes engagement with the casement in a double line of contact encircling the opening. The present invention contemplates the provision of a novel construction whereby an auxiliary frame, such as a screen frame or the frame of a storm sash, may be added without destroying this double seal. The auxiliary frame, furthermore, is disposed 100 upon the inside with respect to the window construction, thereby permitting the main frame to be left open, without requiring that the auxiliary frame also be left open, as is the case in conventional screened closure constructions where 105 110

the screen is hung exteriorly with respect to the closure.

The preferred embodiment of my invention has been illustrated as being cooperatively associated with a steel window casement 11, which comprises a substantially Z-shaped strip 12 substantially encircling the window opening 13. Inasmuch as the casement illustrated is double, i. e. is provided with two window openings 13, the central stile 14 of the casement 11 is common to both openings 13, and therefore, instead of being Z-shaped in cross sectional configuration, is substantially T or I-shaped, as clearly illustrated upon Fig. 2. Hence, a base flange 16 and a bead portion 17 out-standing from the flange 16 are provided, each of which completely encircles one of the window openings 13, these parts 16 and 17 being held in properly spaced relationship by means of the web portion 18 of the strip 12.

The closure frame 21, which is adapted to close each of the openings 13, is also defined by a continuous Z-shaped strip 22, the web 23 of which holds the base flange 24 and the outer flange 26 properly spaced, so that the distance between their respective planes substantially coincides with the distance between the planes of the base flange 16 and the bead 17 of the casement 11. The present invention contemplates the provision of hinges 27 for the closure frame 21, of such a nature that they may be adjusted subsequent to installation, thereby permitting mounting the screen or storm sash at any time that may be desired after completion of the building in which the casement 11 is mounted. These hinges 27, however, are of such a nature that when the screen or storm sash frame is not present the closure frame when closed establishes a double storm-proof seal with the casement 11. This is accomplished as a result of the fact that the base flange 24 of the closure frame 21 engages the base flange 16 of the casement 11 at the same time that engagement takes place between the outer flange 26 of the closure frame 21 and the outer surface of the bead 17 which extends outwards with respect to the base flange 16.

The closure frame 21 is illustrated as being provided with a pane 28 of glass, with the result that light may be admitted through the associated opening 13 when the frame 21 is swung closed, but air currents excluded.

The auxiliary frame 31 is preferably in the form of a channel 32 opening outwards, within which a smaller channel 33 is receivable, the outside width of the smaller channel 33 being sufficiently smaller than the inside width of the channel 32 to permit the reception and retention of the edge 34 of a sheet of wire screen 36 within the channel 32 when the smaller channel 33 is also received therein. These parts establish a relatively tight fit, so as to securely clamp the edges 34 of the screen 36 and hold the screen stretched tightly across the opening 37 defined by the frame 31. It should be understood, however, that whereas the frame 31 is, in the present modification, designed as a screen frame, it is entirely within the scope of the present invention to substitute a second pane of glass or other suitable material for the screen 36, under which circumstances the auxiliary frame 31 would support a storm sash instead of a screen.

The outer edge of the channel 32 of the auxiliary frame 31 is continued in the form of a substantially Z-shaped flange 38, the base 39 of which is adapted to be received between the base flange 16 of the casement 11 and the flange 24

of the closure frame 21, and the outer flange 41 of which is adapted to be received between the outer flange 26 of the frame 21 and the bead 17 of the casement 11. Hence, the imposition of the screen frame 31 between the closure frame 21 and the casement 11 necessitates adjustment of the closure frame 21 in such a manner that it is moved outwards a distance substantially equal to the thickness of the extension 38 of the channel 32. The hinges 27, by means of which the closure frame 21 is mounted, are provided with means for effecting this adjustment.

Each of these hinges 27 comprises a casement leaf 42 secured to the outer face of the casement 11 and extending outwards preferably angularly with respect thereto. The pintle pins 43, which are rigid with the outer ends of these leaves 42, are in axial alignment, permitting the leaves 44 which are secured to the sash frame 21 to be mounted thereupon for pivotal movement, whereby the sash frame 21 can optionally be moved to open or closed position with respect to the casement 11. Instead of being journaled accurately upon the pins 43, however, the sash leaves 44 are provided with substantially oval-shaped holes 46 materially larger than the cross sectional area of the pintle pins 43, and within each of these holes 46 a complementarily shaped bushing 47 is received. Each bushing is provided with a hole 48, within which one of the pintle pins 43 fits accurately, but instead of being midway between the ends of the major axis of the associated oval-shaped bushing 47 the hole 48 is nearer one end than the other of the bushing. Moreover, the major axis of the hole 46 in each of the sash leaves 44 extends substantially perpendicularly with respect to the plane of the sash, with the result that by reversing the bushings 47 within the holes 46 in their respective leaves 44 the effective length of those leaves may be varied. Thus, it may be seen that if the closure construction is installed, without the auxiliary frame 31, the bushings 47 should be turned so that the holes 48 therein are adjacent their outer ends, thereby increasing the effective length of the sash leaves 44 and causing the sash frame 21 to establish the double weather seal with the casement 11, as hereinabove described. However, when it is desired to mount the auxiliary frame 31, the bushings 47 should be reversed, positioning the holes 48 adjacent their inner ends, thus decreasing the effective length of the leaves 44 and spacing the sash frame 21, when closed, outwards from the casement 11 a distance equal to twice the eccentricity of the holes 48 with respect to the center of the major axes of their respective bushings 47.

The auxiliary frame 31 associated with each of the window openings 13 is mounted for pivotal movement about the same axis as that about which the associated closure frame 21 is mounted. This is accomplished by means of the extended pintle pins 43, permitting each of the pintle pins 43 to pivotally receive a leaf 51 connected to the associated auxiliary frame 31. Instead of being rigidly attached to the auxiliary frame 31, however, the hinge leaves 51 carried by each pair of aligned pintle pins 43 is connected to a standard or bracket 52 which is disposed vertically within the space 53 between the webs 18 and 23 of the casement 11 and the closure frame 21 at the hinged side of the closure frame. Means are provided for removably mounting the auxiliary frame 31 upon the vertically extending portion 54 of the bracket 52. Preferably, this

is accomplished by means of a plurality of pins 56 which extend from a face of the vertical portion 54, each pin having a head 57. The flange 38 is provided with a similar number of vertically elongated holes, each of which is of key-hole shape, inasmuch as the lower end is large enough to receive the head 57 of one of the pins 56 therethrough, whereas the upper end of the hole is slightly larger than the shank of the pin 56 but smaller than the head 57. This permits the auxiliary frame 31 to be mounted upon the bracket 52 by engaging the holes in its flange 38 upon the pins 56 of the associated bracket 52, with the frame 31 in slightly elevated position, and then permitting the frame 31 to drop until the pins 56 are seated within the upper smaller ends of the holes, the parts being so proportioned and arranged that when the frame 31 drops in this manner it comes accurately into proper position with respect to the casement 11 and closure frame 21. Each of the leaves 51 is in reality a lateral extension of the vertical portion 54 of the associated bracket 52. However, inasmuch as the conventional arrangement of hinges whereon metal sash are mounted positions the pintle pins 43 extending toward each other from their associated hinge leaves, one of the arms 51 is made up of two sections 58 and 59, releasably united by means of a plurality of screws 61 or their equivalent. This permits mounting the bracket 52 for pivotal movement upon the same hinges as those upon which the closure frame 21 is mounted, by disassembling the two-piece arm 35 or hinge leaf 51, seating the eyes 62 which are provided at the outer ends of the arms 51 upon their respective pintle pins 43, and then reassembling the sections 58 and 59 of the arm 51.

In order to accommodate the arms 51 of each bracket 52, the flange 26 of the closure frame 21 is provided with a slot 63 in the hinged edge of the frame 21 in position to permit each arm 51 to extend therethrough into the vertical space 53. The outermost flange 41 of the Z-shaped strip or flange 38 of the auxiliary frame 31 is also provided with a slot in registry with each of the slots 63 for the reception of the associated arm 51.

Figs. 6, 7 and 8 shows a slightly modified form of hinge construction, whereby the same adjustment of the closure frame 21 may be attained. The pintle pin 66 extends through a closely fitting hole 67 in the casement leaf 68, and preferably a washer 69 of friction material is interposed between the head 71 of the pin 66 and the leaf 68. Another washer 72 of friction material is interposed between the upper surface of the casement leaf 68 and the lower surface of the closure frame leaf 73. An elongated hole 74 is provided in the leaf 73, through which the pin 66 extends, and means are provided for retaining the pin 66 in the outer end of the elongated hole 74, this means being in the form of a metal washer 76 having lugs or ears 77 which are bent down in engagement with the side edges of the leaf 73 to insure turning of the washer 76 with the leaf 73. Another lug 78 is provided upon that edge of the washer 76 which is remote from the window structure, and by bending this lug 78 downwards across the outer end of the leaf 73 when the leaf 73 has been pulled inwards so as to dispose the pin 66 in the outer end of the hole as illustrated upon Fig. 9, the pin 66 may be retained in this end of the hole. This is the position occupied by the leaf 73 and the lug 78 when the auxiliary frame 31 is not mounted upon the window construction,

inasmuch as this arrangement of the parts will result in holding the closure frame 21 rigidly against the casement 11, so as to establish the double weather seal encircling the associated opening 13. When it is desired to mount the auxiliary frame 31, the lug 78 may be bent upwards, whereupon the closure frame 21 may be moved outwards a distance equal to the elongation of the hole 74, thus permitting the reception of the flanges 39 and 41 of the auxiliary frame 31 between the casement 11 and the closure frame 21.

Another washer 79 of friction material encircles the pin 66 above the metal washer 76, and a nut 81 is threaded onto the pin 66 above the washer 79, so as to cause the parts to press against the friction washers with sufficient pressure to establish the desired amount of friction, whereby the closure frame 21 will be retained in adjusted position against the action of wind, and the like.

Another washer 82 of friction material encircles the extended portion 83 of the pin 66 above the nut 81, and the leaf 84, which is connected to the auxiliary frame 31, is removably receivable upon the extension 83 of the pin 66, as clearly shown upon Figs. 6, 7 and 8.

Any suitable latch means may be provided for releasably securing the closure frame 21 and/or the auxiliary frame 31 in closed position. Preferably, this latch construction, which is indicated in its entirety at 86, is of the type disclosed in my aforesaid copending application, and comprises a shank 87 pivotally mounted upon the screen frame 31, and carries a pair of engaging detents 88 and 89. The former of these detents, 88, 110 is adapted to be received within a slot 91 in the stile 14 which separates the two window openings 13, whereas the second detent 89 is adapted to engage an ear 92 which is rigid with the closure frame 21, thereby locking the screen frame 31 115 and close frame 21 together. The inner end of the shank 87 is provided with a handle 93, whereby the latch 86 may be operated.

It is to be understood that the details of the invention as herein disclosed, are subject to alteration within the spirit or scope of the appended claims.

I claim:

1. In a closure construction, a casing encircling an opening, a closure adapted to make sealing engagement therewith along a plurality of lines of contact encircling said opening, means for pivotally mounting said closure upon said casing, and an auxiliary frame adapted to be mounted on said casing and having sealing means 125 adapted to be interposed between said casing and said closure and to make contact with both to establish a multiple seal encircling said opening, said mounting means being adjustable to shift said closure for the reception of said sealing 130 means.

2. In a closure construction, a casing encircling an opening, an outstanding bead on a face of said casing encircling said opening, a pair of aligned pintle pins carried by said casing, a sash frame 140 journaled on said pins and adapted to be swung to closed position wherein said frame engages both said casing and the outer edge of said bead in lines of contact encircling said opening, means for adjusting said frame laterally with respect 145 to said pintle pins to space said frame from said casing and bead, an auxiliary frame, and a flange extending from said auxiliary frame into the space between said casing and said closure.

3. In a closure construction, a casing encircling 150

- an opening, an outstanding bead on a face of said casing encircling said opening, a pair of alined pintle pins carried by said casing, a sash frame journaled on said pins and adapted to be swung to closed position wherein said frame engages both said casing and the outer edge of said bead in lines of contact encircling said opening, means for adjusting said frame laterally with respect to said pintle pins to space said frame from said casing and bead, an auxiliary frame, and a flange extending from said auxiliary frame into the space between said casing and said closure and into the space between said bead and said closure. 80
4. In a closure construction, a casing encircling an opening, an outstanding bead on a face of said casing encircling said opening, a pair of alined pintle pins carried by said casing, a sash frame journaled on said pins and adapted to be swung to closed position wherein said frame engages both said casing and the outer edge of said bead in lines of contact encircling said opening, means for adjusting said frame laterally with respect to said pintle pins to space said frame from said casing and bead, an auxiliary frame, means for mounting said auxiliary frame upon said pintle pins for movement about the axis of pivotal movement of said sash frame, and a flange extending from said auxiliary frame into the space between said casing and said closure and into the space between said bead and said closure. 85
5. In a closure construction, a casing encircling an opening, an outstanding bead on a face of said casing encircling said opening, a pair of alined pintle pins carried by said casing, a sash frame journaled on said pins and adapted to be swung to closed position wherein said frame engages both said casing and the outer edge of said bead in lines of contact encircling said opening, means for adjusting said frame laterally with respect to said pintle pins to space said frame from said casing and bead, an auxiliary frame, means for mounting said auxiliary frame upon said pintle pins for movement about the axis of pivotal movement of said sash frame, and a flange extending from said auxiliary frame into the space between said casing and said closure and into the space between said bead and said closure. 90
6. In a closure construction, a casing encircling an opening, an outstanding bead on a face of said casing encircling said opening, a pair of alined pintle pins carried by said casing, a sash frame journaled on said pins and adapted to be swung to closed position wherein said frame engages both said casing and the outer edge of said bead in lines of contact encircling said opening, means for adjusting said frame laterally with respect to said pintle pins to space said frame from said casing and bead, an auxiliary frame, means for releasably mounting said auxiliary frame upon said pintle pins for movement about the axis of pivotal movement of said sash frame, and a flange extending from said auxiliary frame into the space between said casing and said closure and into the space between said bead and said closure. 95
7. In a closure construction, a casing encircling an opening, an outstanding bead on a face of said casing encircling said opening, a pair of alined pintle pins carried by said casing, a sash frame journaled on said pins and adapted to be swung to closed position wherein said frame engages both said casing and the outer edge of said bead in lines of contact encircling said opening, means for adjusting said frame laterally with respect to said pintle pins to space said frame from said casing and bead, a bracket, means for mounting said bracket upon said pintle pins for movement about the axis of pivotal movement of said sash frame, an auxiliary frame, means for releasably mounting said auxiliary frame upon said bracket, and a flange extending from said auxiliary frame into the space between said casing and said closure. 100
8. In a closure construction, a casing, a pair of axially alined pintle pins mounted thereon, a closure frame and an auxiliary frame cooperatively associated with said casing, a pair of alined hinge leaves secured to each of said frames, all of said leaves being receivable upon said pintle pins, the leaves associated with said auxiliary frame being disengageably mounted upon said pins, and means for adjusting the leaves of the other frame to alter the position of said closure frame with respect to said pins and compensate for mounting or removal of said auxiliary frame. 105
9. In a closure construction, a casing, a pair of hinge leaves mounted thereupon, a pair of axially alined pintle pins carried by said leaves, a closure frame associated with said casing, a pair of hinge leaves mounted on said frame and engaged upon said pintle pins, an auxiliary frame receivable between said casing and said closure frame, and means on the leaves of at least one of said pairs for adjusting said closure frame outwards from said casing to compensate for the thickness of that portion of said auxiliary frame which is disposed between said casing and said closure frame. 110
10. In a closure construction, a casing, a pair of axially alined pintle pins mounted thereupon, a pair of hinge leaves mounted upon each of said pins, a closure frame mounted upon one of said hinge leaves associated with each of said pins, a bracket mounted upon the other hinge leaf of each of said pins and having a plurality of headed pins extending therefrom, an auxiliary frame having a plurality of vertically elongated holes in an edge thereof, the lower ends of said holes being larger than the upper ends thereof, the heads of said pins being receivable within said lower ends of the holes and larger than the upper ends thereof. 115
11. In a closure construction, a casing, a pair of axially alined pintle pins mounted thereupon, a pair of hinge leaves mounted upon each of said pins, a closure frame mounted upon one of said hinge leaves associated with each of said pins, a bracket comprising a vertical member, and a pair of arms extending laterally therefrom, one of said arms being in two sections releasably joined and each of said arms being engageable upon one of said pintle pins, an auxiliary frame, and means for mounting said auxiliary frame upon said vertical portion of the bracket. 120
12. In a window construction, the combination with a frame and an outwardly opening sash mounted on said frame, said frame and sash having a plurality of spaced cooperating weathering portions, of an outwardly movable screen mounted on said frame at the inside of said sash. 125
13. In a window construction, the combination with a frame and an outwardly opening sash mounted on said frame, said frame and sash having a plurality of spaced cooperating weathering portions, of an outwardly opening screen mounted on and overlapping said frame at the inside of said sash. 130
14. In a window construction, the combination with a frame and an outwardly opening sash 135
- 75

mounted on said frame, said frame and sash having a plurality of spaced cooperating weathering portions, of an outwardly movable closure mounted on and overlapping said frame at the inside of said sash.

5 15. In a window construction, the combination with a frame, comprising bars having flanged

main portions and flanged portions inside said main portions, of an outwardly opening sash mounted on said frame and comprising flanged bars, and an outwardly movable closure mounted on and overlapping said flanged portions at the 80 inside of said sash.
